UNITED STATES PATENT OFFICE.

JAMES H. MARSH, OF NEW YORK, N. Y.

PEN.

1,285,296.

Specification of Letters Patent. Patented Nov. 19, 1918.

Application filed April 1, 1918. Serial No. 225,928.

To all whom it may concern:

Be it known that I, JAMES H. MARSH, a citizen of the United States, residing at New York, county of New York, and State of New York, have invented new and useful Improvements in Pens, of which the following is a specification.

This invention relates to that class of pens in which a solid stick of pigment is fed into a chamber located in the feed bar, where the ink is dissolved by combining it with a quantity of water.

The invention is designed to include a large stick of ink with a rotary device, controlled by the operator to move the ink slowly into the mixing chamber of the feed bar.

The novel features of the invention are more fully described in the following specification and claims, and illustrated in the accompanying drawing in which:

Figure 1 represents a sectional side elevation of a pen, embodying this invention.

Fig. 2 is a side view of a spiral sleeve.

Fig. 3 is a similar view of a slotted sleeve.

Fig. 4 is a horizontal section taken along the line 4—4 of Fig. 1.

Fig. 5 is a detail view of a feed bar.

Fig. 6 is a horizontal section taken along the line 6—6 of Fig. 1 on a larger scale.

In this drawing the numeral 12 designates a barrel or shell open on the top, and at its lower end is provided with a holder 13 screwed into the barrel. A feed bar 14 is fixed or inserted into the holder, and located in the bar is a chamber 15 for mixing the ink. The bar is provided with an annular mouth 16 at its upper end, leading to or communicating with the chamber. Lateral openings 17 extend through the walls of the feed bar, so that the water will freely flow into the chamber. A pen or nib 18 is frictionally held between the holder and feed bar, and the curved shank of the pen covers the mixing chamber as indicated in Fig. 6.

An actuating cap 19 is mounted on the upper open end of the barrel and the spiral sleeve 20 is secured to the cap. In this sleeve is arranged a sleeve 21, having a longitudinal slot 22 for guiding a pin 23, secured to a clamping ring 24 sliding in the sleeve.

In order to prevent rotation of the slotted sleeve, it is connected at its lower end to the

barrel by means of a tongue and groove 25 or other permanent fastening to prevent withdrawal from the barrel. A stick of pigment 26 is carried by the ring by inserting one end of the stick into the ring. This ring can be split as is well known, and by its resiliency firmly holds the stick.

As shown in Fig. 1, the pen is equipped with a cap 27, which when the pen is in use can be slipped over the top of the barrel, and when it is desired to carry the pen in the pocket, it can be inserted over the bottom end to cover and protect the pen point.

It will be seen that when the cap 19 is rotated it operates the spiral sleeve to move the pin 23 in a rectilinear path along the slot 22, thus forcing the lower end of the pigment into the mouth of the mixing chamber. When the pen point is dipped into water it will trickle through the interstices or joints between the shank of the pen and the barrel, thereby dissolving a small quantity of the pigment projecting into the mixing chamber.

The feed bar will control the flow of ink from the mixing chamber to the pen point. When the ink stick has been used, it can be replaced by another merely by removing the holder 13 and inserting the end of the stick into the resilient clamp. The mixing chamber constitutes a reservoir for holding a quantity of water converted into ink by its contact with the end of the stick, and the feed bar permits minute portions of the mixture to gravitate to the pen point.

I claim:

1. In a pen the combination with a feed bar having a mixing chamber, of a rotary device for feeding a stick of pigment to the mixing chamber.

2. In a pen the combination with a feed bar having a mixing chamber, of a rotary device for feeding a stick of pigment in a rectilinear path into the mixing chamber.

3. In a pen the combination with a feed bar having a mixing chamber, of a spiral rotary device for feeding a stick of pigment into the mixing chamber.

4. In a pen the combination with a feed bar having a mixing chamber, of a spiral rotary device for feeding a stick of pigment in a rectilinear path into the mixing chamber.

5. In a pen comprising a barrel, a feed bar having a mixing chamber carried by a barrel, a cap mounted on the barrel, a spiral sleeve secured to the cap, and a pigment 5 curing clamp slidingly connected to the spiral for feeding the pigment toward the mixing chamber.

In testimony whereof I have hereunto set my hand in the presence of two subscribing witnesses.

JAMES H. MARSH.
